UNITED STATES PATENT OFFICE.

ALBIN F. GOETZE, OF NEWARK, NEW JERSEY, ASSIGNOR TO MORGAN KNITTING MILLS, INC., OF NEWARK, NEW JERSEY, A CORPORATION OF NEW JERSEY.

STITCH AND METHOD OF FORMING THE SAME.

Application filed May 4, 1927. Serial No. 188,753.

This invention relates to an improved stitch for knit garments and to the method of forming the same.

The object of the invention is to provide an improved stitch and method whereby different kinds of garments may be knit and provided with a special knit structure for all of the garment or for part of the garment.

Another object of the invention is to provide a stitch and method whereby the stitch may be used continuously in the manufacture of garments or intermittently.

A further object of the invention is to provide a stitch and method of forming the same wherein a loose appearing looped formation is presented simulating hand knitting.

In the accompanying drawings—

Figure 1 is a fragmentary transverse sectional view through what is known as a flat knitting machine, the same being used to form the stitch to carry out the method of the invention.

Figure 2 is a diagrammatical view showing the motion of the needles.

Figure 3 is a side view of part of the structure shown in Figure 1, illustrating how certain of the needles are left out or discarded.

Figure 4 is an enlarged fragmentary view of a piece of knit fabric showing the effect of racking.

Figure 5 is a fragmentary view illustrating the position of the loops when a set of loops are formed and then discarded.

Figure 6 is an enlarged view of a stretched piece of fabric.

Figure 7 is a view on a reduced scale showing the effect of racking and the loose open hand simulating stitch embodying the invention.

Figure 8 is a view similar to Figure 7 but on a large scale.

Figure 9 is a plan view of a small section of fabric showing a row of loops made and discarded but the cloth not pulled out.

Figure 10 is a sectional view through Figure 9 on line 10—10.

In producing a stitch when using the method embodying the invention, a flat machine is used as shown in Figure 1, said flat machine being of the usual construction and provided with a racking lever 1 for racking the loops in a well known manner. The front bed 2 carries a number of needles 3 which function during the formation of the stitch while the jacks 4 are permanently dis-

carded. The rear plate is provided with the usual number of needles 6, said needles functioning continually. As indicated in Figure 3, there is preferably every third jack 4 discarded, though a greater or less number could be discarded without departing from the spirit of the invention. After the jacks 4 have been discarded as shown in Figures 1 and 3, the machine is racked by pushing downwardly on lever 1 and then the cam of the machine caused to travel in one direction. Lever 1 is moved a second time and the parts moved back from the second stroke. After this has been done, the lever 1 is moved down to the third position and the cam again shifted to produce a row of loops. The lever 1 is then gradually moved back up to its former position and then this operation is repeated. The racking operation distorts the loops so as to produce the wavy effect shown in Figures 7 and 8 and also produce the arrangement shown in Figure 4. This assists in producing the loose effect shown in Figures 7 and 8 when the knit goods has been completed.

Preferably eleven rows of loops are formed and then all of the needles 3 are moved up manually by a plate or other instrument whereby upon the next actuation of the cam, said cam will merely pull the needles back to the position shown in Figure 1 without forming a new loop. The machine is then operated until eleven more rows of loops are formed and then this action is repeated, namely, needles 3 are moved upwardly a sufficient distance to be out of the way of the cam except to be moved down to a position by the cam as the same passes. When the needles 3 are moved upwardly manually, they will pass up through the loops 7 for instance, shown in Figure 1 and then when the cam moves them downwardly again the needles will pass through these loops and allow the loops to become free so that the needles will at this movement be without any loops. On the next actuation of the needles 3 they will engage the yarn and form loops in the usual manner and will continue to form loops which are interlocked with the loops of needles 6 until the needles 3 are again manually moved upwardly. It will thus be seen that the needles 3 form loops which are discarded on each twelfth movement of the machine. As the machine operates, the fabric 8 is knit and in order to secure the desired results, a

suitable weight 9 is connected with the fabric 8 for pulling the same. This weight will cause the discarded loops to unravel and in fact, the eleven former loops formed by the 5 front needles 3 will be unravelled, thus presenting to the other loops substantially twice the amount of yarn for each loop and by reason of the fact that loops have been formed, a kinked or crimped appearance will be presented as well as a loose knit formation as 10 shown in Figure 8. If the loose formation shown in Figure 8 was stretched until the parts were tight, it would appear substantially as shown in Figure 6 except the edge 15 formation, which formation is formed by using all of the needles on both sides of the machine.

From Figures 9 and 10 it will be noted how immediately after the loop 7 has been discarded, the needles 3 will form loops through 20 the next adjacent loops of the needles 6 so that the knitting operation is continued with front and rear looped formations, the front looped formation being later unravelled and 25 allowed to move into the rear loops to produce the effect shown in Figure 8 which simulates the usual hand knitting now in vogue. In case the weight 9 is not used, the front loops will not become unravelled as there is 30 no strain to secure this result. In a case of this kind it will be necessary to stretch the fabric manually and thereby pull out the loops formed by the front needles in order 35 that the effect shown in Figure 8 may be secured. As the unravelling of the front loops is produced by temporarily discarding needles 3 every twelfth run or some other run, it will be evident that all or any part of the body of a knit piece of goods may have the 40 loose formation shown in Figure 8. If desired, part of the garment may have this loose formation and part the usual knit formation with loops on both sides of the needles remaining in the fabric. Also, by not 45 throwing out the needles at the edges of the garment as shown in Figure 7, comparatively

tightly knit edge sections are presented which will not unravel while a loose central body is presented. This will, under certain circumstances, present a pleasing piece of knit goods 50 and also present a good foundation for stitching when the goods is connected together to form a built-up or manufactured garment, as for instance, a sweater.

55

What I claim is:

1. The method of forming a stitch comprising the use of a flat knitting machine for knitting a piece of fabric, discarding permanently certain needles on the front plate, continually racking the knitting machine 60 during the knitting operation, knitting with the remaining needles in the usual manner for a series of rows, discarding one set of loops formed by the needles on the front plate, continuing the knitting operation in 65 the usual manner, and finally pulling the knit fabric until all of the loops formed by the needles on the front plate are unravelled.

2. The method of forming a stitch in knit fabric comprising knitting a piece of fabric 70 on a flat machine, continually racking the knitting machine during the knitting operation, permanently discarding certain needles on one side of the machine, forming and discarding at spaced intervals a row of loops on 75 the side of the machine having said discarded needles, and subjecting the fabric to a weight acting longitudinally on the fabric until all of the loops are unravelled on the side where said loops have been discarded.

3. The method of forming a stitch in knit fabrics comprising knitting a piece of fabric on a flat knitting machine, continually racking the knitting machine during the knitting operation, discarding one row of loops on one 85 side of the machine at certain intervals, and then stretching the finished fabric to cause all the loops to unravel formed by the needles from the side of the machine having the row of discarded loops.

ALBIN F. GOETZE.
